UNITED STATES PATENT OFFICE.

DAVID J. CONANT, OF SAN JOSE, CALIFORNIA.

PUMP CONSTRUCTION.

Application filed November 1, 1921. Serial No. 512,151.

To all whom it may concern:

Be it known that I, DAVID J. CONANT, a citizen of the United States, and resident of San Jose, in the county of Santa Clara and State of California, have invented certain new and useful Improvements in Pump Construction, of which the following is a specification.

It is the object of my invention to provide 10 a form of pump construction wherein the shaft may be supported by a minimum number of bearings in a stack of pump bowls; wherein an arrangement of bowls and bearing is provided whereby the water pressure 15 is so distributed and controlled as to prevent the forcing of sand into the bearing, and to permit proper lubrication of the bearing without wastage, whereby to provide a serviceably lubricated bearing or bearings 20 which will continually support the runner shaft and prevent wear of the runner against the bowl; wherein substantial economy is effected in the size and weight of the pump bowls and the cost of their manufacture and 25 assembly; wherein a means is provided for inserting a section in the shaft at the point of its engagement with the bearing thereby effecting certain economies as hereinafter set forth, and wherein water trapped within a pump bowl is utilized to effect proper 30 lubrication of a pump bearing.

In the drawing—

Figure 1 is a longitudinal section through a pump embodying my invention.

Figure 2 is a sectional view thru another embodiment of my invention.

Figure 3 is a sectional view thru still another embodiment of my invention.

Referring more particularly to the drawing, 1 indicates a bearing for shaft 2 supported by webs 3 and bearing bowl 4. An annular recess 5 is shown in bearing 1 connected to a suitable lubricant supply not shown by conduit 6 in one web 3, and pipe 7, but lubricating means may or may not be provided as desired.

Bearing bowl 4 is provided with an internally threaded flange 8 at one end and an externally threaded flange 9 at the other end whereby the several bowls may be secured together in alignment as shown, the impeller bowls 10 being threaded in a like manner.

Each impeller bowl is provided with dif-

fusion vanes as 11 supporting a neck 12 ⁵⁵ thereby forming an impeller chamber 13 in which is arranged an impeller 14 provided with a neck 15 and mounted on shaft 2, and operating in recess 15^a in neck 12.

The neck portion 12 of each bowl is short ⁶⁰ and the passage 16 therein through which shaft 2 passes is sufficiently large to permit the circulation of water therethrough around shaft 2, this circulation taking place in the direction indicated by the small arrows. In ⁶⁵ other words, the neck portions 12 of the several bowls are not bearings but simply form the inner walls of passages 17 through which the water passes from one impeller to the next. The neck portions 15 of the impellers provide no bearing surfaces but are metallic packings or free running sleeves which are so arranged with relation to necks 12 as to hinder the passage of water around neck portions 12, but not entirely prevent ⁷⁰ its flow.

Considering the pump to be in full operation, the main body of water flows through the several bowls as indicated by the large arrows. The centrifugal force generated by the revolving impeller 14 throws water outwardly into passage 17, this centrifugal force together with the water pressure at 18 causing a circulation of water around each neck portion 12 as indicated ⁸⁵ by the small arrows. A similar circulation of water takes place through the passage 19 between the lower surface of each impeller and the adjacent surface of the next lower bowl. These somewhat free minor circulations around each impeller forms a water leakage between each impeller and adjacent ⁹⁰ surfaces which is necessary to a free turning impeller. This circulation is reduced within practical limits by the construction ⁹⁵ described.

Since no bearings are provided for shaft 2 in these several bowls they may be made shorter than would otherwise be possible and consequently a stack of a given number ¹⁰⁰ of bowls materially shortened. Reducing the length of this stack, of course, reduces its weight as a whole and the weight of individual parts, effects decided economy in manufacture, and increases the efficiency and ¹⁰⁵ materially lengthens the life of the finished product.

The single bearing 1 in a construction of

this type will satisfactorily support a shaft carrying a number of impellers as it is perfectly lubricated at all times and erosive material such as sand is effectually prevented from entering the same.

This perfect lubrication is secured by the following means. The impeller operating immediately above the bearing 1 receives the water from the bearing bowl and throws it out into passage 17 thereby reducing the head of water at point 20 to a uniform pressure with that surrounding the bearing so that oil supplied to the inside of the bearing will traverse the entire length of the bearing without being affected by water circulation, and sand carried by the water would not be carried to the bearing.

The impeller operating immediately below the lower end of bearing 1 creates a circulation of water around neck portion 12 as described thereby relieving the pressure at point 21 of the bearing so that the bearing is lubricated clear to its lower end.

As a still further improvement I have provided a shaft section as 22 provided with a threaded pin at each end as 23-24 to engage threaded sockets 25-26 in the ends of the adjoining shaft sections. This construction permits the easy replacing of a worn bearing, and permits the use of such material as may be most permanent for the bearing portion of a shaft but too expensive to use for the whole shaft.

It is clear from the above description that I have provided a construction by means of which the desired objects and advantages are obtained. By means of the construction described the impellers are maintained in perfect axial alignment with their respective bowls and consequently wear against the bowls is practically eliminated and the life of the pump materially prolonged.

In Figure 2 I show an embodiment of my invention in which a conduit 27 extends from chamber 28 in impeller bowl 10 down to conduit 6 and bearing 1. In this type of impeller bowl a long neck 12 is provided and the settling chamber 28 formed in the casting of the bowl by means of a core, the support for which form holes as 29-29 in the bottom wall of the chamber. The water flowing between neck 12 and impeller 14 fills chamber 28 and maintains a pressure therein greater than that at points 20 and 21 on the bearing below. Consequently by connecting chamber 28 and bearing 1 a leakage of water is provided into bearing 1 at its central point, this water leakage passing both ways through bearing 1 and discharging therefrom at points 20 and 21. This water leakage is constant since the pressure in chamber 28 is always greater than the pressure on bearing 1, the latter being placed below said chamber, and the lubrication is efficient because the outward move-

ment of the water through bearing 1 effectually prevents the entrance of sand and other erosive materials thereto. Since the movement of water through conduit 27 is but slight, the water in chamber 28 remains almost stationary; therefore any sand or other foreign material carried into the chamber will settle on the bottom thereof. This being the case the water drawn off for lubricating purposes is clear and entirely free of all substances that might score or wear the shaft or bearing. If thought desirable a filter may be inserted in chamber 10 as indicated at 30.

In Figure 3 still another embodiment is shown in which the core holes are at 31 and an opening is provided at 32 into passage 16 whereby the pressure in passage 16, chamber 10 and bearing 1 are equalized. This equalization of pressures prevents circulation through bearing 1 above holes 31 and consequently prevents the entrance of sand thereto. There would of course be some little circulation below holes 31 but this circulation is reduced by neck portion 15 fitting somewhat snugly in recess 15^a, any wear occasioned by said circulation being of little moment since the shaft and impeller are held in position by the bearing 1 proper.

It is to be understood of course that while I have herein shown and described one embodiment of my invention, this disclosure is to be considered as illustrative only and changes in form, construction and method of operation may be made within the scope of the appended claims.

I claim:

1. An impeller bowl having an impeller chamber formed therein and having a passage formed therein communicating with said impeller chamber and of greater diameter than the shaft passing therethrough, and having an annular recess formed therein between said chamber and passage and concentric therewith, a shaft and an impeller arranged in said bowl, and means carried by said shaft to engage said recess, the space between said bowl and said means being less than the space between said bowl and shaft.

2. An impeller bowl having an impeller chamber formed therein and having a passage formed therein communicating with said impeller chamber and of greater diameter than the shaft passing therethrough, and having an annular recess formed therein between said chamber and passage and concentric therewith, a shaft and an impeller arranged in said bowl, and means carried by said shaft to engage said recess, and restrict the flow of water therethrough.

3. A pump structure comprising a bearing bowl, a pump shaft arranged therein, an impeller bowl operatively connected to

each end thereof and provided with a part said shaft and bearing bowl intermediate closely encompassing said shaft but spaced a distance therefrom and spaced a distance from the adjacent ends of the bearing portion of said bearing bowl, an impeller operatively mounted in each impeller bowl, means for introducing a lubricant between

for permitting a restricted circulation of 10 water between said impeller bowls and their respective impellers.

DAVID J. CONANT.
